UNITED STATES PATENT OFFICE.

BAPTISTE HILBERT, OF WORCESTER, MASSACHUSETTS.

SHEDDING MECHANISM FOR LOOMS.

SPECIFICATION forming part of Letters Patent No. 695,609, dated March 18, 1902.

Application filed August 7, 1897. Serial No. 647,425. (No model.)

To all whom it may concern:

Be it known that I, BAPTISTE HILBERT, a citizen of the United States, residing at Worcester, in the county of Worcester and State of Massachusetts, have invented a new and useful Improvement in Shedding Mechanism for Looms, of which the following is a specification, accompanied by drawings forming a part of the same, in which—

10 Figure 1 represents a side view of the shedding mechanism of a loom. Fig. 2 is a side view of the same with the frame on the side next the beholder removed in order to disclose the operating mechanism. Fig. 3 is a 15 side view of the shedding mechanism, showing the side opposite that shown in Fig. 1. Fig. 4 represents a portion of the shedding mechanism, showing one of the sliding jacks in its lowest position and engaged by the 20 lower reciprocating knife. Fig. 5 represents a portion of the shedding mechanism, showing the jack in its central position and disengaged from both upper and lower reciprocating knives. Fig. 6 is a similar view showing 25 the jack in its highest position and engaged by the upper reciprocating knife; and Fig. 7 represents, on a larger scale, the spring-actuated sliding pin by which the inner ends of the jacks are lifted.

30 Similar letters and reference-figures refer to similar parts in the different figures.

Referring to the drawings, A denotes a portion of the framework forming the head of a loom and supporting the shedding mechanism, said framework consisting of two similar side frames, between which is located the operative mechanism for raising and lowering the harness-frames. Journaled in the framework A is a horizontal shaft 1, which is rotated from the crank-shaft 2 by means of the vertical shaft 3 and beveled gears 4 and 5. The shaft 1 carries upon one end a crank-plate 6, which is connected by a link 7 with a lever 8, attached to a rocking shaft 9, having a similar lever 10 upon its opposite end.

40 The levers 8 and 10 have their upper ends connected by links 11 with the upper knife-bar 12, and their lower ends are connected by links 13 with the lower knife-bar 14, so that 45 the oscillation of the levers 8 and 10 will impart a reciprocating motion to the knife-bars 12 and 14 in horizontal slots 15 and 16. Be-

tween the upper and lower knife-bars 12 and 14 are arranged a series of jacks 17, lying in a horizontal plane and provided with notches 55 18 in their upper edges and similar notches 19 in their lower edges, which are adapted to be engaged by the upper and lower knife-bars, respectively, for the purpose of imparting a longitudinally-sliding motion to the 60 jacks 17.

The upper ends of the jacks 17 are provided with teeth 20, engaging segmental gear-wheels 21, which turn loosely upon a horizontal shaft 22. Each of the gear-wheels 21 is 65 provided with a radial arm 23, pivotally connected by means of a link 24 with the vertical arm of a bell-crank 25, which rocks upon a rod 26, held in the frame A.

70 The arms of the bell-cranks 25 have notched ends 27, to which are attached the harness-straps 28 and 29, connecting the bell-cranks 25 with the harness-frames (not shown) of the loom in the usual and well-known manner. Journaled in horizontal bearings in the frame 75 A is a pattern-chain roll 30, which carries a pattern-chain 31, consisting of a series of spindles 32, having their ends united by the links 33 of an endless chain and carrying a series of rolls 34 and a series of larger rolls 80 35, about twice the diameter of the smaller rolls 34. The rolls 34 and 35 are arranged upon the spindles 32, so as to be carried beneath the jack 17 as the pattern-chain is rotated. 85

An intermittent rotary motion is given to the pattern-chain roll 30 by means of a star-wheel 36, carried upon the pattern-roll shaft, and a driving-wheel 37, carried upon the shaft 1 and provided with spurs 38 and segmental faces 39, forming, with the star-wheel 36, the familiar mechanical movement known as the "Geneva stop-motion," by which the pattern-chain roll is locked in position between each movement. The horizontal jack 95 17 rests by gravity upon the pattern-chain, and as the spindles 32 are successively brought beneath the jacks those jacks which are engaged by the larger rolls 35 will be raised high enough to have their upper notches 18 100 engaged by the upper reciprocating knife-bar 12, and those jacks which rest upon the spindles 32 will be allowed to fall low enough to bring their lower notches 19 into engagement.

with the lower reciprocating knife-bar 14, while those jacks which are supported upon the smaller series of rolls 34 will be held midway between the upper and lower reciprocating knife-bars 12 and 14 and out of engagement with both.

The operative mechanism is so timed that when the upper and lower reciprocating knife-bars 12 and 14 are at either end of their travel the intermittent movement of the pattern-chain will be completed, bringing one of the spindles 32 directly beneath the jacks 17, so as to carry them either into their upper, lower, or intermediate position, in accordance with the arrangement of the rolls, thereby carrying such of the jacks as are to be moved by the upper knife-bar into engagement therewith, and such of the jacks as are to be moved by the lower knife-bar are allowed to fall into engagement therewith, while those jacks which are to remain at rest are held upon the smaller rolls 34 in an intermediate position between the two knife-bars. Stop-rods 40 are held in the frame A beneath the radial arms 23 and slightly below the axis of the gears 21, so as to check the rotation of the gear-wheels, and the radial arms are held in close contact with the stop-rods 40 by means of the pullingsprings 41, which connect the links 24 with the lower arms of the bell-cranks 25.

A cross-bar 42 extends beneath the inner ends of the jacks 17 and supports a series of sliding pins 43, which are pushed up against the inner ends of the jacks by means of spiral springs 44 in order to offset the weight of the inner ends of the jacks and insure the engagement of the jacks with the lower knife-bar, the pressure of the spring-actuated pins 43 causing the jacks to be rocked upon a fixed bar 45, which supports the jacks immediately beneath the gear-wheels 21. In Figs. 4, 5, and 6 I have represented the three positions assumed by the jacks as they are controlled by the movement of the pattern-chain and illustrating the motion of the jacks upon the fixed bar 45.

The notches 18 and 19 in the jacks 17 are provided with shoulders at each end of the notches, so that the jacks are capable of being moved in either direction by the engagement of their notches with a reciprocating knife-bar. For example, the jack shown in Fig. 4 is represented as engaged with the lower knife-bar 14, so it will be carried outward by the next movement of the knife-bar 14; but in case at the time of changing the pattern-chain knife-bar 12 was at the inner end of its slot 15 then the jack would be moved out by being raised, carrying the notch 18 into engagement with the upper knife-bar.

A simultaneous reciprocation of the upper

and lower knife-bars 12 and 14 is made at each pick of the loom, the upper bar 12 moving in one direction and the lower bar 14 in the opposite direction at one pick, with their motions reversed at the next succeeding pick, so that any of the jacks can be moved at every pick of the loom by simply holding it continuously in engagement with either the upper or lower knife-bar. This result is secured by making the notches 18 and 19 with shoulders at each end of the notch, so that the jack can be moved in opposite directions by the same knife-bar, and providing means for carrying the jacks into engagement with either of the knife-bars at either end of their movement and holding them out of engagement with both knife-bars in case the harness-frames are to remain at rest, thereby allowing the knife-bars to be moved at a uniform and slower speed for the same speed of the loom, obviating the necessity of a quick return movement of the knife-bars.

What I claim as my invention, and desire to secure by Letters Patent, is—

1. The combination with a series of sliding jacks provided with rack-teeth, of segmental gears engaging said rack-teeth, harness-frame levers operatively connected with said gears, and a series of spring-actuated pins applied beneath the inner ends of said sliding jacks to counterbalance the weight of said inner ends, substantially as described.

2. The combination of a series of rocking segmental gears, fixed pins by which their motion is limited; sliding jacks provided with rack-teeth engaging said segmental gears, radial arms projecting from said gears, a series of bell-crank levers operatively connected with the harness-frames, links connecting one of the arms of said bell-crank levers with the radial arms of said gears, and springs connecting said links with the outer arms of said bell-crank levers, whereby said gears are held against said fixed pins at each end of their movement, substantially as described.

3. The combination of a series of rocking segmental gears, toothed jacks engaging said gears, reciprocating knife-bars engaging said jacks, a transverse supporting-bar beneath said jacks, spring-actuated pins bearing against the inner ends of said jacks on one side of said transverse supporting-bar in order to counterbalance said inner ends of the jacks and depress the outer ends, substantially as described.

Dated this 31st day of July, 1897.

BAPTISTE HILBERT.
